(57) **CLAIM**

The ornamental design for a contoured kneepad, as shown and described.

DESCRIPTION

FIG. 1 is a perspective view (as seen from the front view) of the contoured kneepad.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a perspective view (as seen from the back view) thereof.

The broken lines depict portions of the contoured kneepad that form no part of the claimed design.
